UNITED STATES PATENT OFFICE.

BLOOM V. KAGA, OF ROCKAWAY, OHIO.

RAILWAY-TIE.

No. 908,272.

Specification of Letters Patent. Patented Dec. 29, 1908.

Application filed October 2, 1907. Serial No. 895,556.

To all whom it may concern:

Be it known that I, BLOOM V. KAGA, a citizen of the United States, residing at Rockaway, in the county of Seneca and State of Ohio, have invented certain new and useful Improvements in Railway-Ties, of which the following is a specification.

My invention relates to an improvement in steel ties, and the object is to provide a hollow tie having supporting plates over the top adapted to strengthen the tie and sustain the weight of the rails and the rolling stock traveling thereon.

The invention consists in certain other novel features of construction and combination of parts which will be hereinafter fully described and pointed out in the claim.

In the accompanying drawings, Figure 1 is a view in perspective; Fig. 2 is a longitudinal sectional view; and Fig. 3 is an end view.

A represents the hollow U shaped metal tie and 1 is an opening formed in the bottom of the tie to permit water to issue through. Plates 2, 2 extend across the top of the tie and fit in the notches B, B in the sides of the tie and have flanges 3, 3 which extend down over the sides and bolts 4 passing there through secure them to the tie. Extending downwardly from the plates 2 at their inner ends is a brace 5, which fits against the sides of the tie and extends to or along the bottom thereof and affords a support for the plates as well as the sides of the tie preventing them from collapsing, and by means of the flanges 3 on the plate the tie is prevented from spreading. The ridge 6 is formed on the plates 2 against

which the rails 7 abut and slots 8 are formed on the plates for the reception of bolts 9 which extend through clamps 10, 10 and the latter overlap the flanges of the rail and rest diagonally against the web whereby the rail is rigidly held in position.

This tie can be used for any size rail and the plates 2, 2 may be adjusted along the top of the tie to suit the requirements. It can be manufactured cheaply and consists of few parts which are simple in construction and which can be very readily assembled.

It is evident that slight changes might be made in the form and arrangement of the several parts described without departing from the spirit and scope of my invention, and hence I do not desire to limit myself to the exact construction herein set forth, but:

Having fully described my invention, what I desire to secure by Letters Patent is:

A tie comprising a base and side members, said side members having notches in their upper edges, plates received in the notches, flanges on the plates extending along the sides of the tie, means for securing the plates to the sides of the tie, braces extending from the plates between the sides of the tie, ridges on the plates against which the rails bear, and clamps adjustably connected to the plates for securing the rails in position.

In testimony whereof I affix my signature in presence of two witnesses.

BLOOM V. KAGA.
